COUPLING

Hiram R. Harding, Baltimore, Md., assignor of fifty per cent to Harry E. Karr, Baltimore County, Md., and twenty-five per cent to Logan C. Harding, Hopewell, Va.

Original application December 26, 1947, Serial No. 793,917, now Patent No. 2,469,111, dated May 3, 1949. Divided and this application November 27, 1948, Serial No. 62,355.

3 Claims. (Cl. 285—75)

1

This invention relates to couplings and unions for piping, and more particularly to those for the attachment of tubing, and is a divisional application of that shown in Patent No. 2,469,111, issued May 3, 1949, for Locked Coupling.

In a particular form of coupling for tubing, the end of the tubing is flared out as it enters the coupling without any support being afforded to the walls of the tubing adjacent thereto. This induces stresses in the tubing that render its tightness uncertain as well as causes weakness at the line of entrance enabling it to bend readily and break off. This is particularly objectionable because of the desirability of having that portion of the juncture particularly strong. In this invention, the tubing is passed into a hollow plug so that a substantial portion of the tubing will be encompassed by its wall and supported thereby and place the end of the tubing deep in the plug where the flaring will not affect its structural strength, outside of the coupling. Other details are provided to increase the practical utility of the device and render it more desirable for the work it is intended for.

It is therefore an object of the present invention to provide a new and improved coupling device that will avoid one or more of the disadvantages and limitations of the prior art.

Another object of the invention is to provide a new and improved coupling device that will be strong, readily manipulated, effective and relatively simple in structure.

Other objects will become apparent as the invention is more fully outlined.

For a more complete understanding of the invention, its objects and principles thereof, a particular form of the invention is indicated in the accompanying drawings by way of example. These drawings in conjunction with the following description facilitate the explanation while the claims emphasize the scope of the invention.

Referring to the drawings:

Figure 1 is a longitudinal view of a coupling embodying this invention, a portion being in section to show its interior construction;

Figure 2 is an elevation showing one of the plugs before it is screwed into the coupling, a portion being in section to show its interior construction;

Figure 3 is a longitudinal view of a modified form of coupling, a portion being in section to show its inner construction; and

Figure 4 is an elevation showing one of the plugs before it is screwed into the coupling, a

2

portion being in section to show its interior construction.

Similar reference numerals throughout the drawings serve to point out the same parts.

5 In the form shown in Figures 1 and 2, the tubing 70 if preferably made of copper, aluminum or other similar material, the end portions 71 are provided with flared out walls 72 that project upwardly and outwardly to an enlarged cylindrical section or collar 73 which prevent the tubing from becoming disengaged from the lock fitting member 74, as indicated. The cap element 75 is symmetrically formed to include a hexagonal exterior surface 76 for use with a wrench, while 10 interiorly its wall surfaces 77 are tapered to bind against the inwardly converging surfaces 78 of the wedge nut 85. The latter are held and screwed onto the ends of a nipple member 79 that is provided with a central hexagonal portion 80 for turning purposes, and a central passage 81 therethrough. The end portions 82 of the nipple member are exteriorly chamfered and restricted to facilitate the placing of the funnel end 83 of the tubing 70 thereon and forcing them 15 to bend between the bevelled surface 82 and undercut 84 of the nipple. The wedge nut 85 has its outer portions 86 of hexagonal nut form to allow the use of a wrench thereon and the passage 87 in this portion is cylindrical in form to hold the tubing 70 securely. The wedge nut in this instance is provided with an under cut 88 which is connected with the walls of the passage 87 by an angular faced portion 90 which binds the tube securely to the nipple member 79 when the wedge nut 85 is screwed thereon. The wedge nut is provided with a peripheral groove 92 and the cap 75 is provided with an inwardly turned flange 93 that fits in the groove 92 under the extending lip 95, so as to be locked in place thereon. The wedge nut element 85 has its upper portion 96 exteriorly tapered and is provided with slots 97 longitudinally placed therein to divide 20 same into sections 98.

In the modified form shown in Figure 3, the pipes 50 are preferably of soft material such as copper tubing and the like. The end portions 52 being funneled in shape to fit in their respective wedge nut elements 54 as indicated. Its sections 55 are similar to those shown and described for Figures 1 and 2.

The cap element 56 is symmetrically formed to include a hexagonal exterior surface 57 for use with a wrench, while interiorly its wall surfaces 58 are tapered to bind against the inwardly converging surfaces 59 of the elements 54. The lat-

ter are held and screwed onto a middle nipple member 60. For this purpose the threads 61 are provided on the interior of the elements 54 and the threads 63 on the exterior of the member 60. The end portions 62 are exteriorly chamfered and restricted to facilitate the placing of the funnel ends 52 of the tubing thereon and forcing them to bend between the bevelled surfaces 62 and 64 of the elements 54. This forms a tight joint and one that cannot be dislodged. The cap element 56 has a middle threaded partition 67 that screws onto the nipple 60 as indicated. The entrances to the tapered interiors of the cap elements 56 are bevelled at 68 to permit the sections 55 to enter easily therein. The wedge nut elements 54 have their outer end portions 69 of hexagonal nut form to allow for the use of a wrench thereon and the passage 99 in this portion is cylindrical in form to hold the tubing 50 securely. Room for adjusting the elements 54 and tubing 50 is provided in the cap element 56 and the cooperating construction in the wedge element 54.

Both forms of the invention are effective in preventing leakage at the coupling where the tubing is inserted, as the end portion of the tubing is kept deep in the coupling and its wall is supported substantially by the bases of the plugs. The tubing is encompassed for an appreciable distance within the plug before its end portion is forcibly expressed into a flare. This prevents the tubing from suffering from vibration and takes the greater stresses off the flared portion. It is not intended to limit the term coupling to that of its usual limited meaning, but to include joints between common piping, in addition to tubing, and also ducts in which the device would be appropriately applicable.

While but two general forms of the invention are shown in the drawings and described in the specifications it is not desired to limit this application for patent to these particular forms or in any other way otherwise than limited by the scope thereof, as it is appreciated that other forms could be made that would use the same principles and come within the scope of the appended claims.

Having thus described the invention, what is claimed is:

1. A coupling of the class described comprising in combination, a nipple member externally screw threaded throughout the greater portion of its length except adjacent the ends where it is unthreaded and terminated with a bevel, a cap element mounted on said nipple internally screw threaded for adjustment thereon longitudinally and including a tapered bell-like chamber therein about its longitudinal axis, a wedge nut having walls extending from its base into said chamber and coacting therewith in wedge-like manner when forced therein, said nut including screw threads on its interior adjustable on said nipple and having a recess tapering therefrom formed to permit the insertion of the end portion of a tubing therein for a substantial distance thereof through the wedge nut into the recess and between its encompassing walls and those of

the nipple for holding the tubing tight in the coupling as the nut, plug and nipple are screwed on to each other.

2. A coupling of the class described comprising in combination, a nipple member externally screw threaded throughout the greater portion of its length except adjacent the ends where it is unthreaded and terminated with a bevel, a cap element mounted on said nipple internally screw threaded for adjustment thereon longitudinally and including a tapered bell-like chamber therein about its longitudinal axis, a wedge nut having walls extending from its base into said chamber and coacting therewith in wedge-like manner when forced therein, said nut including screw threads on its interior adjustable on said nipple and having a recess tapering therefrom formed to permit the insertion of the end portion of a tubing therein for a substantial distance thereof through the wedge nut into the recess and between its encompassing walls and those of the nipple for holding the tubing tight in the coupling as the nut, plug and nipple are screwed on to each other, said wedge nuts being slotted to permit resilient compression of its end portion on the tubing as it is screwed as aforesaid.

3. A coupling of the class described comprising in combination, a nipple member externally screw threaded throughout the greater portion of its length except adjacent the ends where it is unthreaded and terminated with a bevel, a cap element mounted on said nipple internally screw threaded for adjustment thereon longitudinally and including a tapered bell-like chamber therein about its longitudinal axis, a wedge nut having walls extending from its base into said chamber and coacting therewith in wedge-like manner when forced therein, said nut including screw threads on its interior adjustable on said nipple and having a recess tapering therefrom formed to permit the insertion of the end portion of a tubing therein for a substantial distance thereof through the wedge nut into the recess and between its encompassing walls and those of the nipple for holding the tubing tight in the coupling as the nut, plug and nipple are screwed on to each other, said wedge nuts being slotted to permit resilient compression of its end portion on the tubing as it is screwed as aforesaid, said recess and end portion of the nipple being of funnel like formation coacting with each other to encompass said tubing end portion into a flared form of plural angular formation.
